UNITED STATES PATENT OFFICE.

WILBUR B. CLAFLIN, OF KANSAS CITY, MISSOURI.

NEEDLE-HOLDER FOR TALKING-MACHINES

No. 917,925.

Specification of Letters Patent. Patented April 13, 1909.

Application filed March 20, 1908. Serial No. 422,227.

To all whom it may concern:

Be it known that I, WILBUR B. CLAFLIN, a citizen of the United States, residing at Kansas City, in the county of Jackson and State of Missouri, have invented new and useful Improvements in Needle-Holders for Talking-Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a needle holder for talking machines and more particularly to a device for holding thorn needles or points for use with such machines.

The needle ordinarily used for this purpose 20 is composed of a metal body having a sharp point and a blunt shank, the latter being held in a socket in a bracket carried by the sound box by means of a set screw, which screw is carried by the bracket and tightened against 25 the needle shank.

While the use of a thorn or wooden needle is well known, it has been found difficult to carry such needles in a manner to secure the best results therefrom, owing to the fact that 30 when attached to the sound box in the usual manner, the pith in the portion of the thorn against which the set screw impinges, allows the thorn shell to give inwardly when pressed by the set screw, thereby causing the needle 35 to loosen and mar the tone of the machine.

It is the object of my invention to provide a device for holding such needles so as to obviate the loosening noted and thereby secure a full rich tone therefrom, and in accomplishing this I have provided the improved 40 details of structure which will presently be more fully described and pointed out in the claims, reference being had to the accompanying drawings, in which:—

45 Figure I is a perspective view of an ordinary sound box equipped with a needle and needle holder constructed according to my invention. Fig. II is an enlarged detail view of a portion of the needle bracket, together with the needle holder and point, showing the relative position of the different parts. Fig. III is a view of the needle holder showing the manner of inserting the thorn point. Fig. IV is a top plan view of the 50 holder. Fig. V is a transverse sectional view of the holder bracket on the line V—V, Fig. II.

Referring more in detail to the parts:— 1 designates a sound box and 2 a needle bracket which may be of any ordinary and well known construction, the latter being provided with a socket 3 and a set screw 4 by means of which a needle or needle holder may be rigidly held in position.

5 designates a point holder having an offset socket member 6 and a shank 7 which latter is adapted to fit within the socket 3 of bracket 2. Extending through member 6 is a socket 8 which is preferably of a cone shape and projected at a slight inward angle as indicated in Figs. II, III, and IV.

9 designates the tapering needle point which is adapted to fit within socket 8 with its sharpened portion projecting through the small end of the socket in position for projection into the record grooves and with its 75 blunt end preferably in the plane of the top of member 6, so that when the holder is deposited in the bracket, the upper end of the point may bear against the lower end of the bracket and be held firmly in place to 80 obviate loosening when the machine is in operation.

While the needle may be cut to the proper length to fit the holder, as described, the best results are obtained when a thorn or 85 needle of greater length is used, when the point of the thorn is inserted into the socket 8 and the enlarged end broken off, as indicated in Fig. III, in this way securing a close, tight fit of the point within its socket and 90 insuring an engagement of the upper end of the point against the bracket member.

In using my device the sound box and needle bracket are arranged and operated in the manner usual with any well known type 95 of talking machine. When it is desired to insert a needle the holder member 5 is removed from the bracket and a thorn projected into and through the socket 8 and pressed until a tight fit is secured, when the 100 upper end of the thorn is broken off as indicated in Fig. III. The holder shank is then inserted into the bracket socket with the upper face of the socket member 6 engaging the lower end of the bracket, and the set 105 screw 3 is tightened against the holder shank to hold the parts in position. The needle is then placed in the record groove in the usual way and the machine operated, the point being held against displacement by its engagement with the lower end of the bracket 110 although the close fit of the point within the

holder socket is ordinarily sufficient to prevent displacement.

After the record is played and a new needle is desired, the holder is removed from the bracket after loosening the metal screw and the needle point removed from the holder by pressing the projecting point against a hard substance, a new point inserted and the holder replaced in the bracket.

10 Having thus described my invention what I claim as new therein and desire to secure by Letters Patent is:—

1. In a needle for talking machines, a point holder having a shank member, and a laterally projecting socket member having a downwardly and inwardly projecting socket, substantially as set forth.

2. In a needle holder for talking machines a holder shank provided with a laterally projecting socket member having a socket taper-

ing longitudinally and toward the shank body, said socket member being adapted to receive and hold a tapered needle point wholly by the fit of such point therein.

3. A needle holder for talking machines 25 comprising a needle bracket, a point holder having a shank member adapted for projection into said bracket and a laterally projecting socket member having a conoidal socket extending therethrough and inclined toward 30 the shank body, said socket member being free from binding parts but said bracket being provided with means for anchoring said shank therein, substantially as set forth.

In testimony whereof I affix my signature 35 in presence of two witnesses.

WILBUR B. CLAFLIN.
